UNITED STATES PATENT OFFICE.

ADOLPH SCHNEIDER, OF CHICAGO, ILLINOIS, ASSIGNOR TO BANNING & BANNING, OF CHICAGO, ILLINOIS, A FIRM COMPOSED OF THOMAS A. BANNING, SAMUEL W. BANNING, AND WALKER BANNING.

BOTTLE-FILLING MACHINE.

1,132,218.

Specification of Letters Patent.

Patented Mar. 16, 1915.

Application filed June 29, 1911, Serial No. 636,025. Renewed January 19, 1914. Serial No. 813,111.

To all whom it may concern:

Be it known that I, ADOLPH SCHNEIDER, a citizen of the United States, residing at Chicago, in the county of Cook and State of Illinois, have invented certain new and useful Improvements in Bottle-Filling Machines, of which the following is a specification.

The present invention relates to that type of mechanism used for the purpose of packaging carbonated liquids, or analogous substances, under pressure.

The objects of the present invention are, to provide a stationary support upon which the to-be filled packages rest during the filling operation; to provide a series of pistons, one of which will actuate the filling tube of the bottle filling mechanism, and the other of which will actuate the sealing head; to provide a series of cylinders for said pistons, one piston being contained in each cylinder; to arrange a system of pressure supply ducts for conveying pressure to said cylinders for the purpose of actuating the pistons; to arrange a series of ducts for exhausting the pressure from the said cylinders; to so arrange these ducts, if desired, as to enable them to perform double functions, namely, that of an inlet and an exhaust duct; to provide an automatically operated valve for controlling the flow of liquid from the source of liquid supply to the filling tube, and in arranging this valve so that it is automatically operated at a time approximately when the filling tube has reached its lowermost position; to provide a method of establishing communication between a source of air pressure less than the pressure of the liquid in the tank and the interior of the bottle; to provide a valve for controlling the flow of said air whereby said valve will be automatically operated to establish said air communication at practically the same time that the communication is established to permit the flow of liquid from the filling tube into the bottle; to provide an arrangement whereby one of the series of pistons may be power driven in both directions, and the other of said pistons may be power driven in one direction only, the last mentioned piston being moved in the opposite direction by contact with the first mentioned piston; and to provide a telescopic connection between the source of

liquid supply and the filling tube, and a telescopic connection between the source of air supply and the sealing head.

Further objects of the invention lie in the compactness of the machine produced by the arrangement of the cylinders and pistons for operating the filling tube and sealing head, and in the utilization of the cross-head connection between the filling tube and the piston operating as a means for establishing connection between the telescopic duct and the filling tube, and providing a continuous passage from the source of liquid supply to the filling tube.

The invention further consists in the features of construction and combination of parts hereinafter described and claimed.

In the drawings, Figure 1 is a side elevation of the mechanisms forming the subject matter of the present invention; Fig. 2, a front elevation of the part shown in Fig. 1; Fig. 3, a side elevation similar to Fig. 1 showing certain of the parts broken away to disclose the arrangement of the pistons within the cylinder, this view showing the parts in raised or non-filling position; Fig. 4, a view similar to Fig. 3 showing the parts in lower or filling position; Fig. 5, a detail partly in section showing the piston which actuates the sealing head, and showing the duct communicating with the lower end of the cylinder in which the pistons for operating the filling tube travels; Fig. 6 a detail partly in section showing the piston for actuating the sealing head, and the piston for actuating the filling tube, and showing the pressure duct which communicates with the upper end of the cylinder in which the filling tube and piston travel, and the upper end of the cylinder in which the sealing tube and piston travel; Fig. 7, a detail partly in section showing the sealing head and filling tube, the connection between the filling tube and the piston operating the same, the connection between the source of liquor supply and filling tube, and the connection between the source of air supply and sealing head; Fig. 8 a section on line 8—8 of Fig. 7; Fig. 9, a section on line 9—9 of Fig. 5 looking in the direction of the arrow; Fig. 10, a section on line 10—10 of Fig. 1 looking in the direction of the arrow with the connection between the sealing head and its piston removed; and Fig. 11, a section

on line 11—11 of Fig. 1 with the connection between the sealing head and its piston removed.

The present invention relates to that type of liquid packaging machines in which the to-be-filled package remains in fixed position, and the filling mechanism is operated to be brought into operative engagement with said package. The machine is designed so that it may, if desired, be used in conjunction with the counter-pressure system described and illustrated in Patent No. 991,093, issued to me May 2, 1911, although, of course, the use of this system is not essential to the carrying out of the present invention.

In bottle filling machines, there are usually a plurality of these filling mechanisms and spout-lift devices arranged around a centrally located tank, but as all of the mechanisms are alike and as all of them operate in exactly the same manner, only one has been illustrated, and only one will be described. But, it is understood that in a complete machine, one or more of these mechanisms may be employed as desired, and the arrangement may be varied to suit the idea of the builder.

The device of the present invention consists of a main cylinder 12 which is divided transversely by a partition or cross-wall 13, so that there is formed in effect an upper cylinder 14, and a lower cylinder 15. These cylinders are arranged end to end, and may be classified as tandemly arranged cylinders.

Mounted within the cylinder 14 is a piston 16, and within the cylinder 15 is a piston 17. Adjacent the lower end of the cylinder 15 is an air hole 15^a to prevent an air cushion being formed below the piston 15 and preventing its descent. The piston 16 has extending therefrom an upwardly extending piston rod 18 which is joined to a cross-head 19 which in turn is connected to a filling tube 20. The piston 17 has secured thereto a stem 21 or sleeve 21 which is connected to a pipe 22 through the medium of a suitable coupling 23. As shown more clearly in Fig. 6, the piston 16 has attached thereto a piston rod 24 which extends in the opposite direction from the piston rod 18, said rod 24 passing through the cross-wall 13 and extending into the hollow interior of the sleeve 21. A series of pins or lugs 24^a are attached to the piston, which act as stop members to limit the movements of said piston.

A suitable packing 25 is employed where the rod 24 passes through the wall 13 so that there is no danger of a passage of pressure between the interior of the upper and lower cylinders. The rod 24 terminates in an enlargement 26 which is designed to engage the piston 17, said engagement being brought about in the form shown by providing an inwardly extending flange 27 on the sleeve 21 with which said enlargement engages.

and as will be seen from a study of Fig. 5, this sleeve is screw-threaded onto the piston 17; and hence when the engagement is effected between the enlarged end 26 and the inwardly extending flange 27 the piston 17 will be moved in the direction of movement of the rod 24 by such engagement. Both pistons are actuated by a medium under pressure, preferably compressed air, and means have to be necessarily provided for the conduction of this pressure to the cylinders, and for the eduction therefrom.

The mechanism which I have illustrated to carry out this portion of my invention is as follows: The lower cylinder 15 has secured to its lower end a cap 28, and said cap is formed with a lug or projection 29 in which is mounted a rotatable tapered valve 30. Said valve is better illustrated in Figs. 5, 6, and 11, and consists of four passages, 31, 32, 33, and 34. Each of these passages, as shown, are of arcuate formation, and have their open ends extending at approximately right angles to one another. The passages 31 and 32 are for the purpose of controlling the supply of compressed air or other medium which is designed to enter a series of pipes 35 and 36. Each of these pipes has one end thereof secured into a lug 37 fixedly secured adjacent the cross-wall 13.

As will be seen from a study of Fig. 6, the adjacent ends of the pipes are spaced away from one another, and a chamber 38 is formed in the interior of the lug 37 which lies intermediate the adjacent end of these pipes. Leading from this chamber 38 is a by-pass 39, also best shown in Fig. 6, which communicates with the interior of the cylinder 15 at the upper end thereof. The pipe 36 has its upper end entered into a lug 40 secured to a cap piece 41 which is positioned to the upper end of the cylinder 14, and formed in this lug is a passageway 42 communicating with the upper end of the pipe 36 and the interior of the cylinder 14 at the upper end thereof.

The ports 33 and 34 of the valve 30 communicate with a pipe 43 which has its lower end secured to the collar 28, and its upper end secured within the lug 37, and formed in said lug is a passageway 44 which communicates with the upper end of the pipe 43 and with the interior of the cylinder 14 at the lower end of said cylinder.

The operation of this valvular controlled mechanism is as follows: With the ports of the valve shown in the position indicated by the full lines in Figs. 5 and 6, the port 34 is in communication with the main pressure supply passage 45 which leads from a suitable nipple 46, best shown in Figs. 10 and 11, to which may be joined a conduction member for the main source of pressure supply. Said port 34 is also in communication with a passage 47 in the lug 29, so that the pres-

sure medium entering through the passage 45 will flow through the valve passage 34, the passage 47, the pipe 43, the passage 44, and into the lower end of the cylinder 14, 5 and the passage 33 will be out of communication with said pipe. When the valve is turned to bring the passages 33 and 34 into this position, which is the position they assume when pressure is being admitted to 10 raise the piston 16, the port 31 will be in communication with a passage 47 in the lug 29 and with an exhaust port 48 so that the medium above the piston 17 will be passing out through the by-pass 39 into the pipe 35 15 and out through the exhaust port 48, and the medium above the piston 16 will be passing through the passageway 42, pipe 36, chamber 38, pipe 35, and out through the exhaust port; thus, with the valve in the position 20 shown by the full lines in Figs. 5 and 6, pressure is being exhausted from above the pistons 16 and 17 and is being admitted below the piston 16.

It will be noted at this point that there is 25 no arrangement provided for admitting pressure below the piston 17. This is because of the fact that in the arrangement shown, the piston 15 is drawn upwardly by the engagement of the enlarged head 26 with the flange 30 27 of the sleeve 21 so that no positive pressure means is needed which will act directly upon this piston for the purpose of raising it. When the valve is turned, so as to bring the ports into the position shown by the 35 dotted lines in Figs. 5 and 6, pressure will be exhausted from beneath the piston 16, and will be admitted above the pistons 16 and 17. Therefore, upon each quarter turn of said valve, pressure is supplied to the 40 interior of the cylinders to move the piston in an opposite direction to that which they had been moving.

It will be noted that with the valve in one 45 position, the pipe 43 is an induction pipe, and when the valve is turned a quarter revolution said pipe becomes an eduction pipe, and it will also be noted that with the valve in one position, the pipes 35 and 36 are induction pipes, and when said valve is given 50 a quarter revolution said pipes become eduction pipes. I, therefore, employ but two sets of pipes, and by means of the valvular control, I am enabled to utilize these pipes both for induction and eduction purposes, 55 they alternately performing one function and then the other.

The means which I employ for conducting the liquid from the source of liquid supply to the filling tube is perhaps best illustrated 60 in Figs. 1 and 7, and consists in a pipe 49 which is in communication with a nipple 50 leading from a suitable source of liquid supply. Telescoping within this pipe 49 is a pipe 51 which passes through a bushing 52 in the cap piece 41. The pipe 51 is entered

into the cross-head 19, and communicates with a passage 53 therein leading to a chamber 54 also formed in said cross-head. Extending from the chamber 54 and in the opposite direction from the passage 53 is a 70 passage 55, and at the juncture of the passage 55 with the chamber 54 is a suitable shiftable valve 56 formed with a stem 57, and normally held in seated position by the action of a coil spring 58, and the passage 55 75 communicates with the filling tube 20.

From a study of Fig. 7, it will be seen that there is a continuous passage extending between the nipple 50 and the filling tube 20 and that the flow of liquid through said 80 passage is controlled by the movements of the valve 56. It will be further noted that although this passage between the source of liquid supply and the filling tube is continuous, it is capable of being made longer or 85 shorter by reason of the telescopic arrangement of the tube 51 with the tube 49. This is, of course, essential; that is, it is essential to have some connection which is capable of moving with the cross-head, and such 90 movability is made necessary because of the fact that the cross-head 19 and the filling tube 20 are both connected to the piston rod 18, and said piston rod travels up and down in conformity to the movement of the piston, which 95 movement raises and lowers the filling tube into proper position with respect to the interior of the to-be filled package.

The valve 56 is provided for the purpose of providing some means for admitting liquid to the filling tube only at a time when said filling tube is in proper position with respect to the interior of the to-be filled package. By the arrangement shown, the valve is made automatic in its action, and the time of its action is made certain so that it may only act when the filling tube is in proper position within the to-be filled package. As the piston 16 travels downwardly carrying with it the piston rod 18 100 and the cross-head 19, the valve stem 57 will descend until it strikes the upper face of the cap 41 or some other suitable contact. When this contact is effected, the valve will be pushed upward unseating it from the 105 end of the passage 55, and liquid can then pass through said passage into the interior of the filling tube and to the interior of the to-be filled package. It is obvious that if this contact is located in proper position, 110 there can be no actuation of the valve save when the filling tube is in proper position with respect to the interior of the to-be filled package, so there is no danger of an escapement of liquid before the filling tube 115 has reached this proper position, nor is there any danger of an escapement during the raising and lowering of said tube. The timing of the movements to properly control the raising and lowering of the filling 120 125 130

tube is brought about by an arrangement of a series of contacts, not shown, which engage and rotate a star wheel 59 that is connected to the valve 30.

5 As heretofore stated, the piston 17 controls the movements of the sealing head which is designated by the numeral 60. This sealing head is shown more in detail in Fig. 7, and consists of a flaring outer section 61 secured in a lug or extension 62 on a sliding cross-head 63. The sealing head is provided on its interior with a suitable seat 64, preferably formed of compressible material which engages the upper end of the 10 neck of the bottle or to-be filled package, and, as shown, the interior of the sealing head is formed with a passageway 65 through which the filling tube 20 extends. This passageway communicates with a passage 66 leading to a chamber 67 in which is located a suitable check valve 68 for the purpose of preventing a passing of the overflowing liquid therethrough, and leading from the chamber 67 is a passage 69 extending in opposite directions from the passage 66 and communicating with a chamber 70 which communicates with the upper end of the pipe or tube 22.

30 Lying in the interior of the pipe 22 is a tube or pipe 71, which, as shown more clearly in Fig. 7, is of a reduced diameter from the interior bore of the pipe 22, so that a clearance or passageway 72 is provided between said pipes. The pipe 71 extends 35 downwardly a suitable distance into the pipe 22, and has its lower end open. The end of the pipe 22 may, if desired, have secured thereto a suitable pet-cock 73 which is for the purpose of enabling any sediment 40 which may collect in the pipes 22 and 71 to be cleared out therefrom. This pet-cock may not be employed unless it is deemed expedient by the mechanic constructing the machine.

45 The pipe 71 is secured to a coupling member 74 which is secured with a suitable packed connection 75 to a lug 76 extending from or secured to the cap piece 41. This lug 76 has formed therein a chamber 77, and 50 located in said chamber is a slidable valve 78 normally held in seated position against a suitable seat 79 by a coil spring 80, and the stem of said valve terminates in a head 81. Communicating with the chamber 77 is 55 a circuitous passageway 82 which leads from a suitable nipple 83 connected in any suitable manner to a source of air supply. It will be noted that this passageway 82 is formed in the cap piece 41, and the circuitous formation of said passageway is rendered necessary in order that it may avoid 60 communication with the interior of the cylinder 14 which, as will be seen from the drawings, is projecting thereinto. This 65 passageway is for the purpose of conducting

the air which is under a pressure slightly less than the pressure upon the liquid in the tank, such pressure being maintained in the manner shown and described in Letters Patent No. 991,093, issued to me May 2, 1911. 70 This principle briefly is to maintain a body of air within a chamber which will have pressure slightly less than atmospheric, so that as the air is driven from the interior of the to-be filled package by the incoming 75 liquid, it will be displaced against the counter pressure action of the air coming from the chamber. This naturally checks the movement of the outflowing air so that a gradual displacement will take place, and 80 the liquid will enter the bottle with a slow and easy movement preventing any foaming or violent agitation which is extremely undesirable.

By the telescopic arrangement of the 85 pipes 22 and 71, the interior of said pipes will be in constant communication, although the pipe 71 remains fixed with respect to the movement of the sealing head, and the pipe 22 moves with said sealing head. The sealing head is raised or lowered by the action of the piston 17. It might be noted at this point that by referring to Fig. 3, it will be seen that the cylinder 15 is shorter than the cylinder 14. This is because of the fact 95 that the piston 16 which raises and lowers the filling tube has a longer distance to travel than the piston 17 which raises and lowers the filling head. The filling head is brought to a stop by its engagement with 100 the neck of the bottle, or to-be filled package, while the filling tube continues to descend until it reaches a point close to the lower end of the bottle, or to-be filled package; and hence there is a difference in the 105 length of travel of the two members.

The sealing head will reach its period of rest first, and the cross-head 19 which carries the filling tube will continue to descend until it is arrested by some suitable stop 110 member. When it has reached approximately its limit of descent, the cross-head 19 will engage the head 81 of the stem of the valve 78 and force said valve away from its seat 79. The movement of the valve, how- 115 ever, will not be sufficient so that it will close communication between the upper end of the pipe and the chamber 77, and air pressure will flow from said chamber into the pipe 71, into the space 72, into the chamber 70, through the passage 69, into the chamber 67, through the passage 66, into the open end of the sealing head, and thence into the interior of the bottle. This is the course described for the air which has heretofore been referred to as being of pressure 120 slightly less than the pressure on the liquid in the tank. But after the sealing head has been brought into communication with the interior of the bottle, this will be the course 125 130

taken by the air escaping from the bottle, said air passing through the passage 66, and then following the course heretofore described, except that it will enter the elements in reverse order from that heretofore described. In fact, there will be a commingling of the air under atmospheric pressure which is being discharged from the bottle, and the air under a pressure less than the pressure on the liquid in the tank throughout the entire length of the passages and chambers heretofore referred to. By utilizing the cross-head 19 for the purpose of controlling the movements of the valve 78, it will readily be seen that said valve can only be operated and communication established through the various air passages when the filling tube has reached approximately its limit of movement, and this is the timing of the device which is deemed most practical in operation. The support for the to-be filled package is in the form of a shoe 82^a fixedly secured in any suitable manner, and in the form shown, is formed integral with the cross-wall 13. This shoe, it is understood, remains in fixed position so that no movement of the bottle with respect to the filling apparatus is allowed.

The operation of the device will be understood from the foregoing, but briefly is as follows: With the ports of the valve 30 arranged in the position shown by the dotted lines in Figs. 6 and 7, pressure will be admitted above the piston 16 and above the piston 17 driving both of these pistons downwardly within their respective cylinders. The downward movement of the piston 17 will force the stem 21 downwardly carrying the pipe 22 and the cross-head 65, bringing the sealing head 60 into engagement with the upper end of the bottle or to-be filled package. The downward movement of the piston 16 will carry downwardly the piston rod 18, cross head 19, and the filling tube 20, and said downward movement will also force the piston rod 24 downwardly into the interior of the sleeve 21. The piston 16 will continue in its downward movement until it is brought to a stop by any suitable means. When this latter engagement is effected, the valve 56 will be unseated to permit of the passage of liquor from the source of liquid supply through the pipes 49 and 51, into the passages 53, through the chamber 54, into the passage 55, through the filling tube 20, and into the interior of the bottle, or to-be filled package. Practically, simultaneously with the unseating of the valve 56, the cross-head 19 will reach a position where it will engage the head 81 of the valve 78, unseating said valve, and establishing a communication between the interior of the bottle and the source of air which is under a pressure slightly less than the pressure of the liquid in the tank.

The ports will remain in the above described position until the star wheel 59 is engaged by one of its contacts, and rotated so as to bring the ports of the valve 30 into the position shown by the full lines in Figs. 5 and 6. 70 When this is effected, pressure will be admitted beneath the piston 16, and pressure will be exhausted from above said piston, so that said piston will move upwardly in its cylinder, and after it has traveled a pre- 75 determined distance, the enlarged end 26 will contact the flange of the sleeve 21, and after such contact the piston 17 will be carried upwardly in unison with the piston 16, pressure having been previously exhausted 80 from above the piston 17 and the ports being returned to normal position. The movement of the pistons upwardly is arrested by a suitable stop upon the pistons themselves, or in any other suitable manner. 85

I claim:

1. In a machine for packing liquids, the combination of a double chambered cylinder, a piston within each chamber, said chambers and pistons being arranged in vertical alinement, means for raising and lowering said pistons, a sealing head arranged out of vertical alinement with said pistons and exteriorly of said cylinder, a connection between one of said pistons and said sealing head, a filling tube extending through said sealing head, a connection between the said filling tube and the other of said pistons, a source of liquid supply, a valved connection between the said source of liquid supply and the filling tube, and means effecting the escape of air from the to be filled package during the filling operation, substantially as described. 95

2. In a machine for packing liquids, the combination of two vertically alined cylinders, a piston within each cylinder, means for raising and lowering said pistons, a sealing head located exteriorly of said cylinders and out of vertical alinement with said pistons, a connection between one of said pistons and said sealing head, a filling tube extending through said sealing head, and a connection between the other of said pistons and said filling tube, substantially 100 as described. 110

3. In a machine for packaging liquids, the combination of two vertically alined cylinders, a piston within each cylinder, means for raising and lowering said piston, a sealing head located exteriorly of said cylinders and out of vertical alinement with said pistons, a connection between one of said pistons and said sealing head, a filling tube extending through said sealing head, and a 115 connection between the other of said pistons and said filling tube, substantially as described. 120

4. In a machine for packaging liquids, the combination of a cylinder, a partition with- 125

in said cylinder dividing the interior thereof into two vertical alined chambers, a piston within each chamber, means for raising and lowering said pistons, a sealing head located exteriorly of said head and out of vertical alinement with said pistons, a connection between one of said pistons and said sealing head, a filling tube extending through said sealing head, and a connection between 5 the other of said pistons and said filling tube, substantially as described.

5. In a machine for packaging liquids, the combination of a cross plate, two cylinders having their adjacent ends entered into 10 said cross plate whereby two independent vertically alined cylinder chambers are produced, a piston within each cylinder chamber, means for raising and lowering said pistons, a sealing head located exteriorly of 15 said cylinders and out of vertical alinement with said piston, a connection between one of said pistons and said sealing head, a filling tube extending through said sealing head, and a connection between the other of 20 said pistons and said filling tube, substantially as described.

6. In a machine for packaging liquid, the combination of two vertically alined cylinders, a piston within each cylinder, a piston 25 rod on each piston, said rods extending in opposite directions, a stem on one of said pistons, a contact on said stem, means for raising and lowering said piston, a sealing head located exteriorly of said cylinders and 30 out of vertical alinement with said pistons, a connection between one of said pistons and said sealing head, a filling tube extending through said sealing head, a connection between the other of said pistons and said filling 35 tube, and one of said pistons being moved in one direction by engagement with the contact on said stem, substantially as described.

7. In a machine for packaging liquids, the 40 combination of tandemly arranged vertically alined cylinders, a piston within each cylinder, a rod connected to each piston, said rods extending in opposite directions, a stem on one of said pistons, a contact on 45 said stem, means for raising and lowering said piston, a filling tube, a connection between said filling tube and one of said pistons, a sealing head lying exteriorly of said cylinders, and out of vertical alinement with 50 said pistons, a connection between said sealing head and the other of said pistons and one of said pistons being moved in one direction by engagement with the contact on 55 said stem, substantially as described.

8. In a bottle filling machine, the combination of a filling tube, a piston, a member 60 connecting said piston and filling tube, a source of liquid supply, a passage through 65 said connecting member, a connection between said passage and source of liquid sup-

ply, and a valve for controlling the passage of liquid into said filling tube, substantially as described.

9. In a bottle filling machine, the combination of a filling tube, a piston, a cross-head connecting said piston and filling tube, a passage through said cross-head communicating with the filling tube, a source of liquid supply, a connection between said passage and said source of liquid supply, 70 and a valve for controlling the passage of liquid through said passage, substantially as described.

10. In a bottle filling machine, the combination of a filling tube, a piston, a member 80 connecting said piston and filling tube, a source of liquid supply, a passage through said member, a telescoping tube joined to said connecting member and forming a portion of a connection between said passage 85 and the source of liquid supply, and a valve for controlling the passage of liquid through said filling tube, substantially as described.

11. In a bottle filling machine, the combination of a filling tube, a movable cross 90 head, a connection between the cross head and filling tube, a piston for raising and lowering said cross head, a source of liquid supply, a passage through said cross-head, a telescoping tube joined to said cross head 95 and forming a portion of a connection between said passage and the source of liquid supply, and a valve for controlling the flow of said liquid through said passage, substantially as described.

12. In a bottle filling machine, the combination of a filling tube, a piston, a member 100 connecting said piston and filling tube, a source of liquid supply, a passage through said member communicating with said filling tube, a connection between said passage and source of liquid supply, and a valve operated when the piston is approximately at its lowermost position to control the passage of liquid into the to-be filled package, substantially as described.

13. In a bottle filling machine, the combination of a filling tube, a piston, a movable cross head connecting said piston and filling tube, a source of liquid supply, a passage through said cross head communicating with said filling tube, a connection between said passage and said source of liquid supply, and a valve operated when the piston is approximately at its lowermost position to control the passage of fluid into the to-be-filled package, substantially as described.

14. In a bottle filling machine, the combination of a filling tube, a piston, a member 115 connecting said piston and filling tube, a source of liquid supply, a passage through said member communicating with the filling tube, a telescoping tube joined to said member and forming a portion of a connection 120 between said passage and source of liquid 130 supply.

- supply, and a valve operated when the piston is approximately at its lowermost position to control the passage of liquid in the to-be-filled package, substantially as described.
15. In a bottle filling machine, the combination of a cylinder, a division wall within said cylinder, tandemly arranged pistons, one piston within each cylinder, a filling tube, a cross-head connection between one of said pistons and the filling tube, a sealing head, a connection between the other of said pistons and said sealing head, a passage in said cross-head communicating with said filling tube, a source of liquid supply, a connection between said source of liquid supply and said passage, and a valve in said cross-head for controlling the passage of liquid into the filling tube, substantially as described.
- 10 16. In a bottle filling machine, the combination of tandemly arranged cylinders, a piston within each cylinder, a filling tube, a cross-head connection between one of said pistons and the filling tube, a sealing head, a connection between the other of said pistons and said sealing head, a passage in said cross-head communicating with said filling tube, a source of liquid supply, a connection 25 between said source and passage, a shiftable valve carried by said cross-head and controlling said passage, and means for shifting said valve when the piston is approximately at its limit of movement in one direction to establish communication between the source of liquid supply and the filling tube, substantially as described.
- 30 17. In a bottle filling machine, the combination of tandemly arranged cylinders, a piston within each cylinder, means for raising and lowering said pistons, a filling tube, a cross-head connection between one of said pistons and the filling tube, a sealing head, a connection between the other of said pistons and the sealing head, a passage in said cross-head with which the filling tube communicates, a source of liquid supply, a connection 35 between said source of liquid supply and said passage, a valve carried by said cross-head, and a contact engaging said valve when said piston is approximately at the end of its movement in one direction to move it and establish communication between the source of liquid supply and the interior of the filling tube, substantially as described.
- 40 18. In a bottle filling machine, the combination of tandemly arranged cylinders, a piston within each cylinder, a filling tube, a sealing head, a cross head connecting one of said pistons and the filling tube, a connection between the other of said pistons and said sealing head, a passage in said cross head, a source of liquid supply, a telescoping tube forming a portion of a connection be-
- 45 tween said source of liquid supply and said passage, and a valve in said cross head controlling said passage, substantially as described.
- 50 19. In a bottle filling machine, the combination of tandemly arranged cylinders, a piston within each cylinder, means for raising and lowering said pistons, a filling tube, a cross-head connecting one of said pistons and said filling tube, a source of liquid supply, a connection between said source and said cross-head, a passage through the cross-head establishing communication between the source of liquid supply and the filling tube, means for controlling the flow of liquid 55 through said passage, a slidable member in which the sealing head is mounted, a source of pressure supply, a connection between said source of pressure supply and the sealing head, a valve controlling the flow of 60 pressure through said connection, and a stem on said valve adapted to be engaged by said cross-head, said engagement establishing communication between the source of pressure supply and sealing head, substantially as described.
- 65 20. In a bottle filling machine, the combination of two vertically aligned cylinders, a piston within each cylinder, a filling tube, a sealing head lying out of vertical alignment with said pistons, means admitting pressure to and exhausting pressure from said cylinders, valve controlled means for admitting liquid to the filling tube, a slidable member embracing one of said cylinders in which 70 member the sealing head is mounted, a source of air supply and a valve controlled connection between said source of air supply and sealing head embodying a telescoping tube, substantially as described.
- 75 21. In a bottle filling machine, the combination of a filling tube, a sealing head, means for raising and lowering the filling tube and sealing head, a source of liquid supply, a connection between the source of liquid supply and the filling tube, a slidable member in which the sealing head is mounted, a source of pressure supply, means for establishing communication between the source of pressure supply and sealing head embodying a telescoping tube, a valve, controlling communication between the source of pressure supply and the sealing head, and means for unseating said valve when the filling tube is approximately at its lowermost 80 position, substantially as described.
- 85 22. In a bottle filling machine, the combination of tandemly arranged cylinders, a piston within each cylinder, a piston rod for each piston, said rods extending in opposite directions, means for raising and lowering said piston, a filling tube, a cross head located above said cylinders and connecting said filling tube and one of said pistons, a source of liquid supply, a connection 90
- 95 100 105 110 115 120 125 130

between said source of liquid supply and cross head, a valved passage through said cross head communicating with the connection from the source of liquid supply and 5 with the filling tube, a sealing head and a connection between the other of said pistons and the sealing head, substantially as described.

23. In a bottle filling machine, the combination of tandemly arranged cylinders, a piston within each cylinder, means for raising and lowering said pistons, a piston rod carried by each piston, said rods extending in opposite directions, a filling tube, a cross head connecting said filling tube and one of said pistons, a source of liquid supply, a connection between said source of liquid supply and said cross head embodying a telescoping tube, a passage through said 10 cross head communicating with the filling tube and with the connection from the source of liquid supply, valvular means for controlling the flow of liquid through said passage, a sealing head and a connection between the other of said pistons and the sealing head, substantially as described.

24. In a bottle filling machine, the combination of tandemly arranged cylinders, a piston within each cylinder, means for raising and lowering the pistons, a piston rod secured to each of said pistons and extending in opposite directions, a filling tube, a cross head connecting said filling tube and one of said pistons, a source of liquid supply, a connection between said source of liquid supply and said cross head embodying a telescoping tube, a passage to said cross head communicating with the connection from the source of liquid supply and 30 35 40 with the filling tube, a shiftable valve controlling said passage, a contact for engaging and shifting said valve, a sealing head and a connection between the other of said pistons and the sealing head, substantially as described.

25. In a bottle filling machine, the combination of tandemly arranged cylinders, a piston within each cylinder, means for raising and lowering said pistons, a piston rod secured to each of said pistons and extending in opposite directions, a filling tube, a connection between one of said piston rods and the filling tube, a source of liquid supply, a valve connection between said source 50 55 60 65 of liquid supply and filling tube, a sealing head, a slidable member in which the sealing head is mounted, a connection between said slidable member and the other of said piston rods, a source of pressure supply and a connection between said latter source and sealing head embodying a telescoping tube, substantially as described.

26. In a bottle filling machine, the combination of tandemly arranged cylinders, a piston within each cylinder, means for rais-

ing and lowering said pistons, a piston rod secured to each of said pistons, said rods extending in opposite directions, a cross-head connecting one of said piston rods and said filling tube, a source of liquid supply, a connection between said source and filling tube, valvular means for controlling the flow of liquid through said connection, a slidable member in which the sealing head is mounted, a connection between said slidable member and the other of said piston rods, a source of pressure supply, a connection between said source and sealing head, a slidable valve controlling the flow of pressure through said connection, and a stem on 80 said valve adapted to be engaged by said cross-head to move the valve to open position, substantially as described.

27. In a bottle filling machine, the combination of tandemly arranged cylinders, a piston within each cylinder, a filling tube, a connection between one of said pistons and said filling tube, a sealing head, a hollow member depending from the other of said pistons, and connected to said sealing head, 90 a stem on the filling tube piston telescoping within said hollow member, and an enlargement on said stem adapted to engage and move said sealing head piston when the filling tube piston is returned to normal position, substantially as described.

28. In a bottle filling machine, the combination of two cylinders, a piston within each cylinder, means for raising and lowering the pistons, a filling tube, a cross-head connecting one of said pistons and filling tube, a source of liquid supply, a valved connection between said source and filling tube, a hollow member on the other of said pistons connected to said sealing head, a stem on the filling tube piston telescoping in said hollow member, and means for effecting an engagement between said stem and sealing head piston, whereby said piston is returned to normal position by the movements of said 105 110 stem, substantially as described.

29. In a bottle filling machine, the combination of a filling tube, a piston for raising and lowering the filling tube, a sealing head, a piston for raising and lowering the sealing head, means for actuating said pistons, a cross-head connecting the sealing tube and its piston, a source of liquid supply, a valved connection between the filling tube and source of liquid supply, including a series of telescoping tubes, a hollow member depending from the sealing head piston and connected to said sealing head, a stem depending from the filling tube piston and telescoping within said hollow member, and means for effecting an engagement between said stem and sealing head piston, whereby said piston is returned to normal position by the actuation of said stem, substantially as 115 120 125 130 described.

30. In a bottle filling machine, the combination of a filling tube, a sealing head, a piston for raising and lowering the filling tube, a piston for raising and lowering the sealing head, a cross head connecting the filling tube and its piston, a source of liquid supply, a connection between said cross-head and said source of liquid supply, a passage through said cross-head communicating with the connection from the source of liquid supply and the cross-head, a shiftable valve controlling said passage, means for engaging said valve to move it from the seated position, a hollow member depending from the sealing head piston and connected to said sealing head, a stem on the filling tube piston, and means for effecting an engagement between said stem and sealing head piston, whereby the latter is moved in one direction by the movements of said stem, substantially as described.
31. In a bottle filling machine, the combination of a filling tube, a sealing head, a piston for raising and lowering the filling tube, a piston for raising and lowering the sealing head, a source of liquid supply, a valved connection between said source and filling tube, a slideable member in which the sealing head is mounted, a hollow member depending from the sealing head piston and connected to the sealing head, a source of pressure supply, a valved connection between said source and sealing head, a stem on the filling tube piston telescoping in said hollow member, and means for effecting an engagement between said stem and sealing head piston to move said piston in one direction by said engagement, substantially as described.

32. In a bottle filling machine, the combination of a filling tube, a sealing head, a piston for raising and lowering the filling tube, a piston for raising and lowering the sealing head, a source of liquid supply, a valve connection between said source of liquid supply and filling tube, a slideable member carrying the sealing head, a sleeve depending from the sealing head piston and connected to said slideable member, a source of pressure supply and a valve connection between said source of pressure supply and said sealing head embodying a telescoping tube, substantially as described.

33. In a bottle filling machine, the combination of a filling tube, a sealing head, a piston for raising and lowering the filling tube, a piston for raising and lowering the sealing head, a source of liquid supply, a valved connection between said filling tube and the source of liquid supply, a sleeve depending from the sealing head piston, a slideable member in which the sealing head is mounted, a connection between the sleeve and slideable member, a source of pressure supply, a valve controlling means between said source of pressure supply and said sealing head, a contact for unseating said valve actuated by the movement of the filling tube piston, a stem on the filling tube, piston entering said sleeve and means for effecting an engagement between said stem and said sealing head piston whereby the latter piston is moved in one direction by said engagement, substantially as described.

ADOLPH SCHNEIDER.
